ATTORNEY.

UNITED STATES PATENT OFFICE.

JOSEPH F. HANRAHAN, OF LONG ISLAND CITY, NEW YORK.

REFRIGERATION.

Application filed September 29, 1926. Serial No. 138,543.

This invention relates to refrigeration and in particular to means for carrying out an improved means of refrigeration and embodies apparatus which will effectively retard putrefaction in the storing of foodstuffs.

In order to perfectly refrigerate meats, vegetables or the like, it is necessary that one principle be adhered to, that is, that the cold air must be delivered at the floor of a refrigerating chamber. Therefore, it is necessary to provide means for delivering the cold air to the floor before it can flow into the provision chamber so that it will flow over the entire floor surface from wall to opposite wall of the refrigerating chamber and from side wall to side wall thereof, thereby forcing all of the warm air above this column of cold air upwardly to the ceiling. In order to carry out this principle, I have provided a particular construction which embodies refrigerating members or coils adapted to be placed in a special condensation chamber on the wall of the provision chamber through which the cold air will descend and at which point the air will attain its greatest density and weight.

In order to retard putrefaction for the greatest possible length of time to preserve food in its best condition, it is necessary that the cold air be delivered at the floor before it is allowed to flow into the provision preserving chamber. The cold air, descending from the condensing coils or from other refrigerating means in my improved condensing chamber, is the densest and heaviest air in the entire chamber. This cold air, when delivered at the floor, flows over the entire surface thereof and causes the ascension toward the ceiling of the warmer air in the provision chamber. This warmer air, when it reaches the ceiling is continuously flowing into contact with the condensing coils or other refrigerating agents so that odors, gases and germs and the surplus of moisture are eliminated therefrom when the same becomes chilled in contact with the refrigerating means, which produces therein a partial vacuum of the cold air, and due to its increased density, causes the same to fall to the floor in the condensing chamber through the unification of the two greatest forces of the coldest air and the warmest part of the cold air.

It is therefore apparent that a perfect, automatic circulation of air is obtained without the aid of any mechanical construction such as motors, fans, etc., which have been resorted

to heretofore and produce only an inefficient method of refrigeration.

Therefore, a particular object of my invention is to provide a refrigerating chamber in which the warmest part of the cold air is continuously ascending in the provision chamber or over the whole surface thereof because the ascending air meets with no opposing current of air and is therefore forced to ascend by the pressure of the cold air blowing from the condensing chamber into the provision chamber on the floor which creates a perfect and continuous circulation of air in the provision chamber.

To enable others skilled in the art to fully comprehend the underlying features of my invention that they may embody the same in the various modifications in structure and relation contemplated, a drawing depicting a preferred form has been annexed as a part of this disclosure and in such drawing, similar reference characters denote corresponding parts throughout all the views, of which,

Figure 1 is a view in elevational section of a refrigerating chamber having at one end thereof a condensing chamber.

Figure 2 is a sectional view taken on the line 2-2 of Figure 1 showing the arrangement of one of the coils and its control members.

Referring to the drawings in detail, 5 indicates the usual storage chamber having therein a slat flooring 6 and side walls 7, upon or against which are supported the meat, fruit or other products requiring a preservative refrigeration. At one end of the chamber I provide a wall 8 which is spaced at its top and bottom from the bottom 9 and top wall 10 of the chamber and behind which is positioned the refrigerating element 11, these refrigerating elements may, of course, be brine carrying coils, such as illustrated in Figure 2 or there may be positioned therebehind, any type of refrigerant in containers or the refrigerant may be cakes of ice, it being of course understood that they are so positioned behind the wall 8 that the whole constitutes a condensing chamber through which the air must pass and through which it cannot pass without coming into contact with the refrigerating element. At the bottom of this chamber I provide, at the junction of the bottom 9 and the end 12, an obliquely positioned guide board or deflector 13, this being positioned at the bottom of the condensing chamber so that air, in its downward movement, will be deflected by the board 13 and will travel, as in-

dicated by the arrows in Figure 1, along the floor 9 of the chamber 5, the air, of course, passing up through the slotted floor 6 and completely passing around and over the food-stuff positioned on said floor 6. The air will continue along the floor 9 and when it meets the end wall of the chamber 5, it may again be deflected by another deflector 14 so that its path will be upwardly along the side wall 10 beneath the side wall rack 7 through which it may pass to cool the food supported thereagainst, after which, it will find its way along the top 10 of the chamber and will pass between the upper end of the wall or partition 15 8 and the ceiling 10 of the chamber 5 into the condensing chamber and down among the coils 11, as before explained.

As set forth in the preamble, it is absolutely necessary in order to obtain perfect refrigeration, to provide the cold air delivery at the floor of the storage chamber and in order to accomplish this result, I have provided the partition wall 8, which, when the air enters at the top thereof into the condensing chamber, prevents its access into the storage chamber proper, except at the lower edge of the wall 8 and out under the slotted flooring 6. It is evident, of course, that by the time the air is forced around through the many 30 coils in the condensing chamber, it will reach its greatest degree of coldness and therefore, its greatest density and will perform its most effective work in raising the already warmed air in the storage chamber to the ceiling or 35 roof 10 thereof and forcing it again into the condensing chamber, where the operation will continue over and over and with the result that there will be a perfect, automatic circulation of air obtained without the aid of 40 any mechanical construction such as motors, fans and the like, which have heretofore been resorted to in order to provide a circulation of air.

Referring to Figure 2, it will be noted that 45 I have shown one of the coils used to carry a refrigerating element, such for instance, as brine and in this respect, I provide the coil 14 of any suitable nature which is provided at one end with an inlet 15 from any suitable 50 source of supply and which, at the opposite end, is provided with an outlet T 16 to the upper end of which is secured the inverted U-shaped thermometer holding element 17 in which is positioned the thermometer 18, 55 whereby readings of the temperature of the coil contents may be noted. A valve 19 is placed below the thermometer so that the U-shaped member may be flushed at will. The opposite outlet of the T 16 is provided with a coil draining valve 20 and this coil draining valve and valve 19 open into a suitable return receptacle 21 into which the 60 contents of the coil may be caught when it is desired to drain the same or test it for quality.

It is evident, therefore, that by my improved refrigerating apparatus, I have provided means whereby the cold air is delivered to the floor of the storage or provision chamber with the result that putrefaction is retarded and that the air is in continuous movement from refrigerating agent through the food to be preserved and back to the refrigerating chamber again, this circulation being kept up by the difference in pressure of air in the storage and refrigerating chambers so that the air, when warmed, is forced through the refrigerating or condensing chamber about the air coils whereby moisture is removed therefrom and also odors and gases, thereby presenting to the food to be preserved, a fresh air supply and retarding putrefaction of the food acted upon by the air.

It is also evident that I have broken up the air in its movement about the condensing pipe so that the same will be split up into small 85 units by contact with the refrigerating coils, or refrigerating element, and it is absolutely necessary that this be done in order that fresh, odorless air may be swept across the food to be preserved continuously. Perfect refrigeration must be a rarified cold air.

While I have illustrated and described my invention with some degree of particularity, I realize that in practice various alterations therein may be made. I therefore reserve the 95 right and privilege of changing the form of the details of construction or otherwise altering the arrangement of the correlated parts without departing from the spirit of the invention or the scope of the appended claim. 100

Having thus described my invention what I claim as new and desire to secure by United States Letters Patent is:—

The combination with a refrigerating chamber comprising a provision holding room, a slotted provision holding supporting wall spaced from the floor of the room and also from the side wall at one end thereof, of a relatively narrow chamber at the other end of the room, a refrigerating element in 110 said chamber, the upper part of which is substantially against the top of the refrigerating chamber, said narrow chamber being formed by a separating partition having openings in the top and bottom thereof 115 formed by termination of the partition near the top and bottom of the refrigerating chamber, the upper opening constituting an inlet for the warm air in the provision room and the lower constituting an outlet whereby a continuous circulation of air is automatically maintained through the slotted walls of the provision holding chamber, and a deflector at the bottom of the refrigerating chamber for directing the air into the provision chamber 120 supporting wall.

In testimony whereof I affix my signature.
JOSEPH F. HANRAHAN. [L.S.]
